Primary Examiner—Cathron C Brooks*Assistant Examiner*—Deanna Fluegeman(74) *Attorney, Agent, or Firm*—Foley & Lardner LLP(57) **CLAIM**

We claim the ornamental design for a graphical user interface for a display screen, as shown and described.

DESCRIPTION

The FIG. 1 is a front view of the graphical user interface for a display screen.

The ornamental design which is claimed is shown in solid lines in the drawing. The broken lines in the drawing is for illustrative purposes only and form no part of the claimed design.
